UNITED STATES PATENT OFFICE.

RUDOLPH WILTEIN, OF PROCTOR, COLORADO.

DESIGN FOR A BUTTON.

53,871.

Specification for Design.

Patented Sept. 16, 1919.

Application filed March 31, 1919. Serial No. 286,586. Term of patent 7 years.

To all whom it may concern:

Be it known that I, RUDOLPH WILTEIN, a citizen of the United States, residing at Proctor, in the county of Logan and State of Colorado, have invented a new, original, and ornamental Design for a Button, of which the following is a specification, reference being had to the accompanying drawing, forming a part thereof.

The figure is a plan view of the button showing my new design.

I claim:

The ornamental design for a button as shown.

RUDOLPH WILTEIN.

Witnesses:

W. L. STRICKLAND,
J. N. HAMIL.
